UNITED STATES PATENT OFFICE.

HUGH WHEELER SANFORD, OF KNOXVILLE, TENNESSEE.

WHEEL CONSTRUCTION.

1,250,229.

Specification of Letters Patent. Patented Dec. 18, 1917.

Application filed February 4, 1916. Serial No. 76,145.

To all whom it may concern:

Be it known that I, HUGH W. SANFORD, a citizen of the United States, residing at Knoxville, in the county of Knox and State 5 of Tennessee, have invented certain new and useful Improvements in Wheel Construction, of which the following is a specification, reference being had therein to the accompanying drawing.

10 This invention relates to wheel construction, and has reference more particularly to wheels adapted primarily for mining car service, of the general type or character illustrated and described, for example, in

15 the United States Letters-Patent to A. B. Day, No. 1,109,905, dated Sept. 8, 1914, and the prior patent to myself, Reissue No. 13,872 dated January 26, 1915.

In wheel constructions of the character 20 under consideration, considerable study and experimentation has been given to that feature thereof which constitutes the end thrust bearing for the axle, in the movement of the wheels especially when going around 25 curves etc., and while mining car wheels with end thrust bearings such as illustrated in the patents above referred to have gone into extensive use, and proven entirely practicable and highly satisfactory in use, it has 30 been ascertained that an equally efficient bearing can be produced, at a decreased expense, with a less number of parts, and increased wear resisting properties, than is the case with prior constructions, and this 35 may be said to be the main object or purpose of the present invention.

The invention, briefly, may be said to include a wheel having an integral closed end hub part constituting an abutment or end 40 thrust bearing for the axle, upon which the hub is sleeved, the abutment having a relatively hardened or wear resisting surface, as by chilling, whereby to effectively take care of the end thrust without the usual incident wear on the hub cap, and thereby 45 doing away with an independent abutment member or wear disk, as largely employed by others at the present time.

In the type of construction embodied 50 herein, it is possible to preserve the advantages of an extended end thrust bearing surface overlying the entire end, or substantially the entire end of the axle, and at the same time to materially reduce the 55 friction and obviate wear, incident to the engagement between the abutment portion

of the hub end of the axle, it having been ascertained in practice, that a wheel hub chilled at the abutment portion will not wear when contacted by the end of the axle 60 in use.

The invention will be more readily appreciated from the detailed description to follow when considered in connection with the accompanying drawings which form a part 65 hereof, and wherein is disclosed, for the purpose of illustration a convenient and satisfactory embodiment of the invention.

In the drawings, the figure is a longitudinal section of a wheel construction, an embodiment of my invention being illustrated 70 therein.

With more particular reference to the drawings, like reference numerals refer to corresponding parts throughout the several 75 views, in which 1 is a pedestal having a hollow extended end adapted for the reception of a hollow hub 2, preferably integral with the wheel proper 3 having the usual tread surface 4. 5 is an axle projecting from the 80 pedestal into the hollow chamber of the hub 2, which latter is of increased diameter relative to the axle 5 whereby to provide a roller chamber for the reception of suitable roller bearings 6. A closure wall 7 may be 85 provided for the inner end of the hub, said wall having a suitable flange 7^a forming a retaining ring for the terminals or pintles 6^a of the rollers. A suitable key 8 of any 90 approved type, such for instance, as illustrated in the Day patent above referred to may be provided for retaining the hub in place on the pedestal, and likewise suitable packing of grease or the like 9 may be interposed in the space between the hub and 95 adjacent wall of the pedestal.

It is desirable in the present instance to provide a bearing surface for the end of the axle integral with the hub, and to this end, a suitable hub cap 9^a constitutes an 100 integral portion of the hub and a closed end therefor. The hub cap 9^a has a depressed portion 10 forming an inwardly projecting end thrust bearing or abutment part 11 surrounded by an annular recessed part 12 adapted for the reception of the terminals or pintles 6^b of the rollers 6. The annular wall of the abutment member 11 cooperates with the annular flange 7^a of the inner closure wall 7 of the hub to provide 110 retaining means for the rollers, and in this connection, it will be observed that the

abutment member 11 is so proportioned that the diameter thereof is greater than that of the end of the axle whereby the abutment member overlies the outer end of the rollers thereby constituting an abutment surface for the outer end of the rollers as well as an abutment surface for the end of the axle.

It has been found that where the axle and rollers contact with the abutment member of the hub, there is apt to be considerable wear on the hub cap, and in order to obviate this wear, thereby increasing the life of the wheel construction, without the necessity of interposing an abutment member or wear washer, it is proposed herein to provide the abutment member 11 with a relatively hardened portion 13, and in the embodiment of the invention herein, this hardened wear surface is provided by chilling the metal in the formation of the wheel. In the formation of the wheel with the relatively hardened wear surface, to receive the direct impact or end thrust of the axle, it is proposed to concentrate the chill to substantially the diameter of the abutment portion of the hub cap and preferably not of sufficient depth to extend entirely through the hub cap, the chilled portion being designated at 13. In this connection, it is obvious that the chill could be made of any desired depth, but it is very desirable to limit the chilled area whereby to strengthen the wheel structure, since assuming that if the whole hub were chilled it would be quite impracticable to bore the same as is the usual practice, and the end of the wheel hub would become more or less brittle with

the possible result that the shock thereagainst by the axle might break and force the hub cap through the casting. Because of the relatively large diameter of the hardened abutment member, an increased bearing surface for the axle is not only provided but also a hardened wear surface forming an abutment for the ends of the rollers interposed between the axle and hub.

What I claim is:—

In a mining car wheel, the combination of a wheel having a hollow hub adapted for the reception of the end of an axle and of a diameter greater than that of the axle to provide an intermediate roller space, roller bearings positioned in said space and having terminal central projections or pintles, a closure member for the inner end of the hub having a flange overlying the pintles at this end of the roller bearing, said hub having an integral closed outer end with an inwardly projecting thickened centrally disposed abutment part for the axle, said abutment forming with the hub portion an annular recess for the reception of the pintles at the outer end of the roller bearings, and said abutment being chilled at its inner surface, which chilled inner surface is of a size to overlie the outer end of the body portion of the roller bearings as well as the end of the axle.

In testimony whereof I hereunto affix my signature in the presence of two witnesses.

HUGH WHEELER SANFORD.
